UNITED STATES PATENT OFFICE.

FREDERICK E. TURNER, OF KANSAS CITY, MISSOURI, ASSIGNOR TO KANSAS CITY ELEVATOR MANUFACTURING COMPANY, OF KANSAS CITY, MISSOURI, A CORPORATION OF MISSOURI.

COMBINED GEAR AND SHEAVE.

1,409,204.

Specification of Letters Patent. Patented Mar. 14, 1922.

Application filed August 30, 1920. Serial No. 406,760.

To all whom it may concern:

Be it known that I, FREDERICK E. TURNER, a citizen of the United States, residing at Kansas City, in the county of Jackson and 5 State of Missouri, have invented certain new and useful Improvements in Combined Gears and Sheaves; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to a combined gear and sheave particularly adapted for use in connection with elevation hoisting mechanism.

20 One of the objects of the invention is to construct a shaft, a gear rim and a sheave rim of a single piece of metal, the shaft being preferably hollow to provide for the necessary torque between the sheave and the 25 gear.

The sheave gear is generally constructed of bronze whereas the sheave may be constructed of steel or other suitable metal and I have, therefore, provided means whereby 30 the bronze gear may be conveniently fastened to the shaft and I have also provided means for conveniently attaching the sheave thereto.

My invention also contemplates the provision of means for preventing relative 35 movement of the gear with respect to the shaft or of the sheave with respect to the shaft, the construction being such that when the parts are connected together, liability of 40 slippage of any of the parts will be eliminated.

In the drawings,

Fig. 1 is a perspective view of a combined 45 shaft, gear ring and sheave ring showing the gear and the sheave in place, parts being cut away to show the shaft, the sheave rim, the gear rim, the sheave and gear in section.

Fig. 2 is a fragmentary, elevational view 50 of a portion of the gear rim and the gear.

Fig. 3 is a perspective view of a combined 55 shaft, gear ring and sheave ring, showing the gear and sheave in place and looking

from the opposite end to that shown in Fig. 1, and

Fig. 4 is a fragmentary, elevational view 55 of a portion of the sheave rim and the sheave.

Referring now to the drawings by numerals of reference:

1 designates a hollow shaft provided with integral, radial spokes 2 integral with a rim 3. Spaced from the spokes 2 and rim 3 are radial spokes 4 and 5 in spaced relation and staggered one with respect to the other. The 60 spokes 4 are connected by a rim 6 having an offset portion to provide a seat 7 for a flange of the sheave. The spokes 5 are provided with a rim 8 against which one flange 65 of the sheave may rest.

The sheave is shown as consisting of an annulus 9 having inwardly projecting flanges 10 and 11, the flange 10 being provided with an offset portion 10' overlapping the offset portion 7 of the rim 6 while the 70 flange 11 rests against the perimeter of the rim 8, as clearly shown in Fig. 1. The overlapping offset portions 7 and 10' are adapted to be secured together by bolts 12, which pass through them so that the sheave may 75 be fastened to the rim 6. Additional bolts 13 alternating with the bolts 12 extend through the offset portion 10' of the flange 10 and through notched portions in the peripheral offset portion 7 of the flange 6, the 80 latter bolts being adapted to prevent relative rotation movement of the sheave with 85 respect to the rim 6.

The flange 11 rests upon the perimeter of the rim 8 and is supported thereby, the 90 flange 8 being desirable since the sheave is relatively wide and will be subjected to considerable strain when a rope or cable passes around the same and is received in the grooves 14.

The rim 3 supports the worm gear rim 15, having the usual worm gear teeth 16 cut in the perimeter thereof and it is provided with inwardly projecting lugs 17 and 18, those designated 18 being of less length than those 100 designated 17 and alternating therewith. The lugs 17 overlap the rim 3 and are adapted to be secured thereto by bolts 19, which pass through the lugs and through the body portion of the rim 3. The bolts 20 in the 105 lugs 18 align with notches 21 in the perim-

eter of the rim 3 and they are designed to resist the annular strain of the worm gear rim with respect to the rim 3 so that all of the strain will not be exerted against the 5 bolts 19.

It will be observed that the bolts 20 received in the notches between the gear and the rim resist any tendency to relative rotative movement between the gear ring and 10 the rim throughout the entire length of each bolt. That is, in order to effect relative movement between the gear ring and its rim, it would be necessary to disrupt practically the entire bolt. There could be no 15 shearing of the bolt because the bolt extends entirely through the notches between the gear ring and its rim, a material advantage over the arrangement shown for the bolts 19.

The construction just described applies 20 equally to the sheave; therefore, rotative movement of the sheave with respect to its rims will be prevented as effectually as will rotative movement be prevented between the gear ring and its rim.

25 In actual practice the shaft, the spokes and rims for the gear and sheave may be cast as a single piece, the alternating spokes 4 and 5 for the sheave being adapted to equalize the strain about the shaft when the sheave 30 is subjected to strain, the flange 11 of the sheave being shown as fastened to the rim 8 by overlapping lugs 22, through which the bolts 23 pass while the gear may be fastened by its overlapping lugs and bolts in the 35 manner shown so that when the parts are secured together, liability of slippage either of the gear or the sheave will be eliminated and a built-up structure may be readily provided, admirably adapted to perform the 40 service for which the same is intended.

One of the main features of the invention is the construction and arrangement of the gear ring with respect to its rim and the sheave ring with respect to its rims, and 45 particular attention is called to the fact that the rim 3 supports the worm gear 15 having the usual worm gear teeth 16 tucked in the perimeter thereof and that the inwardly projecting lugs 18 are of less length than those 50 designated 17 and alternate therewith.

It will be noticed that the lugs on the gear rim lie on one side of the rim 3 while the lugs for the sheave ring lie on opposite sides 55 of its rims. This is for the purpose of ease

It will also be noted that the outer rim 8

is of less diameter than the inner rim 7, the rim 8 being of such diameter that the lugs 10' may pass over the same in order to be secured to the rim 7. When the sheave rim 60 is applied, however, it may be rigidly fastened by the bolts, as above described, the bolts for the rim 7 being preferably inserted from one side and the bolts for the rim 8 being preferably inserted from the opposite 65 side.

The construction shown has material advantages over similar types in which the hub of the gear and the hub of the sheave are swaged, keyed or pressed upon the shaft 70 since liability of slippage of the parts will be eliminated, the hollow shaft affording the maximum amount of resistance to the torque generated therein during the operation of the machine to which the invention is applied. 75

What I claim and desire to secure by Letters-Patent is:

1. A shaft, spaced rims integral with the shaft, one of said rims of larger diameter 80 than the other, a sheave ring having spaced, inwardly directed flanges of diameters corresponding to those of the rims, ears carried by said flanges for engaging against the rims, and means for securing the ears to the 85 rims.

2. A combined gear and sheave for elevator hoisting mechanism comprising a self-sustaining hollow shaft, a gear-carrying rim cast integral with the shaft, a sheave-carrying rim cast integral with the shaft and in spaced relation with respect to the gear-carrying rim, a removable annulus on the gear-carrying rim, said annulus comprising a gear, and a removable sheave on the sheave-carrying rim, the walls of the hollow shaft, the gear-carrying rim and the sheave-carrying rim being approximately the same thickness to prevent rupture of the parts when the casting is in the process of cooling. 100

3. A combined gear and sheave for elevator hoisting mechanism comprising a hollow shaft, spaced rims on the shaft, one of the rims being of larger diameter than the other, a sheave ring having parallel flanges 105 disposed toward the axis thereof, the flanges being of diameters corresponding to the diameters of the rims, and means for securing the rims and the flanges together.

In testimony whereof I affix my signature. 110

FREDERICK E. TURNER.
